UNITED STATES PATENT OFFICE.

ERNST GUSTAV HOFFMANN, OF NEW ROCHELLE, NEW YORK.

GRINDING BALLS.

No. 868,860.

Specification of Letters Patent.

Patented Oct. 22, 1907.

Application filed May 6, 1907. Serial No. 372,073.

To all whom it may concern:

Be it known that I, ERNST GUSTAV HOFFMANN, a citizen of the United States, residing in the city of New Rochelle, in the State of New York, have invented 5 certain new and useful Improvements in Grinding Balls, of which the following is a specification, reference being had to the accompanying drawing, forming a part hereof.

The grinding of metal balls for ball bearings and 10 other purposes for which accuracy, uniformity and high finish are desirable, is commonly effected in a machine which comprises two disk-like plates of metal, relatively rotatable and pressed yieldingly, one toward the other, concentric grooves being formed in the 15 adjacent faces of the plates or in the face of one of them in which the balls are received, together with an abrasive powder, usually emery powder, mixed with oil. The peripheral speed of the balls in such machines is not the same as the peripheral speed of the 20 portions of the plate or plates against which they are pressed, so that the loose particles of abrasive material between the balls and such portions of the plates are in this manner enabled to act upon the surfaces of the balls. The portion of the ball which is thus removed 25 by a particle of the abrasive material is almost infinitesimal, but each particle of abrasive material nevertheless makes upon the surface of the ball a scratch, the character of which is dependent upon the size and character of the particle. The whole surface 30 of the finished ball, therefore, is made up of a vast number of scratches which are sometimes visible to the naked eye as a sort of cloudiness or dullness upon the surface of the ball and are always plainly apparent when the ball is examined with a microscope of moderate power. The balls finished in this manner therefore leave something to be desired in the way of smoothness and by the present invention it has been discovered 35 that a much greater approach to perfect smoothness of surface, as well as almost mathematically perfect sphericity and accuracy of the balls can be secured by dispensing altogether with the use of loose abrasive material and by carrying on the grinding between two disks or plates, relatively rotatable and one or the other provided with concentric grooves as before, while one of such disks or plates is itself composed 40 of abrasive material. Especially good results are attained if such particles of abrasive material as may be loosened from the plate or disk as it wears away are immediately removed, as by washing them out with a 45 constant and ample flow of a suitable liquid.

The invention will be more fully explained herein after with reference to the accompanying drawing in which is represented so much of a grinding machine as is necessary to enable the invention to be understood, and in which—

Figure 1 is a view in side elevation, partly broken out, of a portion of such a machine, and Fig. 2 is a top view of the same.

In the particular form of mechanism which is chosen for illustration of the nature of the invention 60 a stationary disk A, preferably of metal and having in its working face a series of concentric grooves a, is mounted upon a stationary shaft B, being held from rotation thereon and also from longitudinal movement by any suitable means, such as a pin b passing 65 through the hub of the grinding disk or plate A and the shaft and removable to permit the disk or plate to be moved back upon the shaft when necessary.

A rotating disk or plate C, made of any suitable abrasive material, such as corundum, for example, is 70 mounted to rotate upon the shaft B, being provided for this purpose, in the machine shown, with a suitable wheel or belt pulley D. It is pressed toward the plate or disk A by any suitable means, as a stiff spiral spring E surrounding the shaft B and abutting against 75 an adjustable nut e. The plate or disk C may or may not be provided, when new, with concentric grooves in its working face, which correspond to the grooves a in the working face of the disk or plate A, but such grooves are naturally formed therein as the use of the 80 machine continues.

The balls to be ground, which are shown in place in Fig. 1, may be introduced and removed and interchanged through slots in the disk A and by means of a table G in spiral form, all as fully explained in Letters Patent of the United States No. 803,164, dated October 31, 1905, or by any other suitable means. The operation of the machine shown in the drawing is in general the same as that of the machine described in said Letters Patent, but no emery powder or other 90 loose abrasive material is supplied to the machine, the abrasive action of the disk C being alone relied upon. If this disk is made of suitable material, it will slowly wear away in an impalpable powder, but to prevent any scratching of the balls by particles which 95 may be loosened from the disk it is desirable that they be removed immediately. If the grinding should be done dry, such loose particles would be quickly thrown out or might be blown out by a blast of air suitably directed. The grinding, however, is prefer- 100 ably carried on with a suitable liquid, kerosene oil being found to be well adapted for the purpose, and in order that all loose particles of abrasive material may be immediately removed, a somewhat copious flow of the liquid is maintained throughout the opera- 105 tion. As shown in the drawing the working parts of the machine are mounted over a tank or reservoir H into which the oil or other liquid falls from the grinding disks and in which the particles of abrasive mate- rial and steel are precipitated. From the tank H the 110

oil flows through a pipe *h* to a centrifugal pump *I* by which it is returned to the grinding disks through a pipe *i* by which the oil or other liquid is distributed upon the table *G* from which it passes with the balls 5 through the disk *A* to the grinding surfaces. By such means the particles of metal and of abrasive material are immediately removed from the grinding surfaces and the scratching of the balls thereby is wholly obviated.

10 From the fact that the disk *A* is provided with a series of concentric grooves it will be apparent that the balls do not partake of any radical movement across the disk *C* of abrasive material during the grinding process, from which it follows that in my process 15 the balls always travel in a path or paths concentric with the axis of the rotating disk during the grinding operation. This will result in slight grooves being formed in the abrasive disk when in use, as above pointed out, whereby the area of contact between the 20 abrasive disk and the balls is increased and a better grinding action secured.

While the machine herein shown is well adapted for carrying out the invention, it will, nevertheless, be understood that the invention is not restricted to any 25 particular form or type of machine and that the mech-

anism shown and described herein can be varied as may be found desirable to meet the necessities of different uses.

I claim as my invention:

1. The improvement in the method of grinding balls 30 which consists in grinding them between relatively rotating disks, while they travel in a path concentric with the axis of rotation one of said disks being formed of abrasive material.

2. The improvement in the method of grinding balls 35 which consists in grinding them between relatively rotating disks, while they travel in a path concentric with the axis of rotation, one of said disks being formed of abrasive material, and in immediately removing the loose particles of abrasive material.

3. The improvement in the method of grinding balls 40 which consists in grinding them between relatively rotating disks, while they travel in a series of paths each concentric with the axis of rotation one of said disks being formed of abrasive material, and in constantly washing 45 out the loose abrasive material by means of a suitable liquid.

This specification signed and witnessed this 26th day of April, A. D., 1907.

ERNST GUSTAV HOFFMANN.
